US00D742150S

(12) **United States Design Patent**
Fitzgerald et al.

(10) **Patent No.:** **US D742,150 S**
(45) **Date of Patent:** **** Nov. 3, 2015**

(54) **WIRE SHELVING**

(71) Applicant: **Edsal Manufacturing Co., Inc.**,
Chicago, IL (US)

(72) Inventors: **Scott Fitzgerald**, Lowell, IN (US);
David J. Wojtowicz, Orland Park, IL (US); **Thomas St. Germain**, Bridgeview, IL (US); **Mitch Liss**, Northbrook, IL (US); **Al Dunaj**, Chicago, IL (US)

(73) Assignee: **Edsal Manufacturing Company, Inc.**, Chicago, IL (US)

(**) Term: **14 Years**

(21) Appl. No.: **29/464,476**

(22) Filed: **Aug. 16, 2013**

1,284,235 A 11/1918 Carlin
D230,797 S 3/1974 Slaboden

FIG. 1 is an isometric view of a first embodiment of wire shelving;

FIG. 2 is another isometric view thereof;

FIG. 3 is an elevational front view thereof;

FIG. 4 is a top view thereof;

FIG. 5 is an elevational side view thereof;

FIG. 6 is an isometric view of a second embodiment of wire shelving;

FIG. 7 is another isometric view thereof;

FIG. 8 is an elevational side view thereof;

FIG. 9 is a top view thereof; and,

FIG. 10 is an end view thereof.

The dotted break lines illustrated in FIGS. 1 through 4 and 6 through 9 are not part of the claimed design and represent that no particular length is claimed.

The broken lines are for the purpose of illustrating the environment of the article only and form no part of the claimed design.

1 Claim, 6 Drawing Sheets
